UNITED STATES PATENT OFFICE.

PETER J. LUNATI, OF MEMPHIS, TENNESSEE.

TURNTABLE LIFT.

Application filed June 9, 1925. Serial No. 36,019.

My invention relates to turntable lifts. More particularly it relates to hydraulic or fluid-pressure operated lifts especially adapted for raising automobiles to afford ready access to parts normally relatively inaccessible for oiling, greasing, inspection, cleaning and repair.

One of the objects of my invention is to provide an improved turntable lift.

10 Another object is to provide a safer fluid operated lift.

Another object is to provide a lift which is particularly responsive to application of fluid pressure.

15 Another object is to provide a lift readily accommodated with the usual garage and service station equipment.

Another object is to provide a lift which operates with relatively equal ease in cold 20 weather and in hot weather.

Another object is to provide a lift wherein the return of the mechanism to normal or depressed position is automatically retarded in the event of either accidental or intentional 25 release of pressure.

Another object is to provide a satisfactory air operated turntable lift for automobiles.

Another object is to provide a lift particularly adapted for the oiling of automobiles.

30 Another object is to provide a lift wherein the air required for the lifting operation is utilized to deliver oil under pressure for lubricating purposes.

Another object is to provide a lift which is 35 simple, reliable and relatively inexpensive to operate and maintain.

Other objects and advantages of the invention will be apparent during the course of the following description.

40 In the drawings, I have shown several embodiments of the invention. In this showing—

Figure 1 is a central vertical sectional view through one form of the invention,

45 Figure 2 is an enlarged central vertical sectional view showing a portion of the upper end of the piston and associated elements,

Figure 3 is a similar view of the lower end of the cylinder showing the piston in lowered position,

50 Figure 4 is a perspective view showing a vehicle in position and the piston raised,

Figure 5 is a section on line 5—5 of Figure 2,

55 Figure 6 is a section taken substantially on line 6—6 of Figure 5.

In general my hydraulic turntable lift comprises a hollow stationary cylinder, having a closed bottom and open top, and a movable hollow piston telescopically and rotatably mounted in the cylinder and carrying the automobile supporting superstructure. The cylinder and piston are partly filled with an incompressible fluid such as oil, while air may be injected into the space in the piston above the oil level to effect the raising and maintain the elevation of the piston regardless of the direction the superstructure is turned. In any position of the piston the superstructure may be turned about the axis 60 of the stationary cylinder to provide a turntable effect. The piston is prevented from suddenly dropping if the source of pressure fails and the pressure within the piston is utilized for an oil spraying equipment. 65

Referring to the drawings the numeral 10 designates a lower cylinder section provided at its upper end with a flange 11 to which is bolted an upper cylinder section 12, by bolts 13 or the like. The cylinder sections are 70 adapted to be embedded in the ground and preferably are surrounded by a concrete or similar well 14 to provide reinforcement for the cylinder when pressure is introduced therein in a manner to be described. The 75 lower end of the cylinder section 10 is provided with a cap 15 having a transverse air port 16 therein connected with an air pressure supply pipe 17. As shown diagrammatically in Figure 1 of the drawings, the pipe 80 17 is connected to a three-way valve 18 which has a pair of branch pipes 19 and 20. The pipe 19 opens to the atmosphere while the pipe 20 communicates with the interior of a pressure tank 21 supplied with air pressure 85 from a suitable pump (not shown).

A hollow or tubular piston 22 is arranged to rotate and reciprocate within the cylinder sections as shown in Figure 1. A packing gland 23 surrounds the piston and is bolted 100 as at 24 to an annular flange 25 formed integral with the upper cylinder section as shown. Packing 26 is provided to prevent leakage of oil and air past the piston as will be hereinafter explained. The piston is provided at its lower end with a cap 27 threaded thereon and provided with a depending flange 28 to limit the downward movement of the piston as will be obvious. As shown in Figure 1, the cap 27 is provided with an annular flange 29 having a sliding fit within the lower cylinder section while the piston proper 105 110

is adapted to have a sliding fit within the upper cylinder section. The lower cylinder section is slightly larger in diameter than the upper cylinder section and it will be obvious that the flange 29 is adapted to contact with the lower end of the upper cylinder section to limit the upward movement of the piston. As clearly shown in Figure 3, the cap 27 is provided with a central opening 30 in which is arranged a vertical air pipe 31. The opening 30 is slightly larger in diameter than the pipe 31 to permit the passage of oil through the opening in a manner to be described. The lower end of the pipe 31 is threaded as at 32 within a vertical extension 33 of the air passage 16. The upper end of the air pipe 31 is provided with a T-head 34 as shown in Figure 2 for a purpose to be described. As shown in Figure 1, the cylinder and piston 20 form a two-compartment chamber adapted to contain oil to a level substantially as indicated by the numeral 35 in Figures 1 and 2 with a fluid pressure space above the oil level and a restricted liquid passage between the 25 chamber compartments. It will be obvious that the level of the oil is at all times below the T-head 34 so that it cannot flow into the air pipe 31.

A head indicated as a whole by the numeral 36 is carried by the upper end of the piston as indicated in Figures 1, 2, 5 and 6. This head includes a substantially cylindrical collar 37 which is pressed in position on the upper end of the piston and is provided with an inturned annular flange 38 at its upper end which is adapted to positively limit the downward movement of the collar. The head 36 is further provided with a plurality of outwardly extending arms which are 40 formed integral with the collar 37. Each of these arms includes substantially vertical ribs 39 which are arranged substantially radially of the piston and each of the ribs terminates in its outer end in longitudinal portions 40 as clearly shown in Figure 5. Integral webs 40', which are preferably horizontal, are adapted to reinforce the ribs 39.

The numeral 41 designates as a whole a pair of I beam supporting members each of 50 which includes parallel central portions 42, the webs 43 of which are riveted to the ribs 40 as at 44. Outwardly of the parallel portions 42 the I beams diverge as at 45 and their outer ends are arranged beneath parallel vehicle supporting rails 46. The outer ends of 55 the I beams may be riveted as at 47 or otherwise secured to the rails 46 as will be apparent. As shown in Figures 2 and 6, a cover plate 48 is arranged over the head 36 and associated elements. The plate is preferably secured to the flanges 38 of the head by screws 49. Rivets 50 or other fastening elements pass through the outer edges of the plate 48 and through the upper bases of the I beams 41 60 as shown in Figure 6. It will be obvious that

the plate 48 and its connections to the I beams are adapted to prevent any tendency of the latter to rock downwardly at their outer ends when a vehicle is in position on the rails.

An oil container 51 is arranged within the upper end of the piston 22 as clearly shown in Figure 2. This oil container is provided at its upper end with an outstanding horizontal flange which may be arranged between the cover plate 48 and the flange 38. 75 The oil container is further provided with apertures 53 which communicate with the interior of the piston. A central tube 54 extends throughout the length of the oil container and is provided at its upper end with a flared mouth 55. The plate 48 is provided above the tube 54 with an opening normally closed by a threaded plug 56. An outlet pipe 57 extends through the plate 48 and has its lower end arranged adjacent the bottom of the container 51. Above the plate 48 the pipe 57 is provided with a suitable valve 58 and the pipe is adapted for connection above this valve with a suitable flexible hose (not shown). 90

As shown in Figure 1, a depression 59 surrounds the piston and is preferably circular and of such a diameter as to receive the I beams 45 when the device is in its lowered position. The rails 46 are adapted to rest upon the ground 60 to permit a vehicle to be driven upon the rails 46. 95

The operation of the apparatus is as follows:

With the rails 46 lowered to contact with the ground, a vehicle may be driven thereover to a substantially central position above the piston and cylinder. With the vehicle properly in position the valve 18 may be arranged in the position shown in Figure 1 of the drawings whereby compressed air will be admitted into the upper end of the piston in the space above the oil level therein. The admission of the air will lift the piston as indicated in Figure 1 until the flange 29 contacts with the lower end of the upper cylinder section 12 and will hold the piston and superstructure up as long as the pressure obtains and regardless of any turning of the piston and superstructure. It will be obvious that oil within the piston will flow downwardly through the opening 30 during the lifting operation. The level of the oil will remain substantially stationary as shown in Figure 1 and will under no circumstances flow into the T-head 34. Air pressure is adapted to maintain the vehicle in lifted position as long as desired. While the piston is held up by the air pressure it is capable of unrestricted rotation about its axis. When it is desired to lower the vehicle the valve 18 may be rotated through an angle of 90° in a clockwise direction as viewed in Figure 1 whereby communication will be established between the interior of the piston and the atmosphere. 110 115 120 125

The weight of the vehicle and the movable parts of the apparatus will then cause the piston to move downwardly, and downward movement will be retarded by the dashpot action of the relatively small opening 30.

As shown in Figures 4 and 7, access may be had to the bottom of the vehicle throughout the greater portion of its length since there are no braces or other elements arranged between the rails other than the I beams 41. Since the centers of the I beams are spaced and their ends diverge outwardly it will be apparent that mechanics may move along the bottom of the car from the ends thereof to the head 36. As previously stated the pressure of the air within the cylinder 22 is communicated to the interior of the oil container through the openings 53 and a suitable hose may be connected to the upper end of the pipe 57 above the valve 58 whereby the springs may be sprayed with oil by opening the valve 58. It will be obvious however that any suitable lubricating medium may be arranged in the container 51 for filling oil cups or the like beneath the vehicle. The air pressure which maintains the piston in raised position will pump oil from the container 51 through the pipe 57 as long as desired and flow of oil may be cut off merely by closing the valve 58. The piston and cylinder may be filled with oil by removing the plug 56 and allowing the oil to flow downwardly through the tube 54. When the piston and cylinder are being thus filled with oil it will be apparent that the T-head 34 will prevent the oil from flowing downwardly into the air pipe 31.

It will be obvious that it is desired to provide means for preventing sudden accidental downward movement of the vehicle while mechanics are working thereunder. The cylinder sections are surrounded by the concrete well 14 to provide reinforcement therefor to prevent the walls of the cylinder from blowing out under the influence of the pressure therein. Should the pressure within the piston and cylinder be released due to breakage of any of the other parts, such as the blowing out of the plug 56, it will be obvious that the downward movement of the vehicle will be retarded by the dashpot action of the opening 30 thus allowing a mechanic working beneath the vehicle to escape before the piston reaches its lower position.

While it has been pointed out that the springs, oil cups, etc., may be lubricated while the vehicle is in raised position it will be obvious that any desired mechanical work may be performed while the vehicle is elevated. Under some conditions it is desirable to tilt the vehicle and this readily may be done by driving either end of the car upon the rails 46 and placing chocks against the wheels whereupon the piston may be lifted in the manner described and the vehicle tilted due

to the fact that two of the wheels remain upon the ground. The ample space provided between the rails will permit the mechanic to work freely upon the vehicle.

From the foregoing description the means for lifting and lowering the vehicle will be apparent. Under some conditions it is desirable to permit the vehicle to leave the rails in a different direction from that at which it approaches. Under such conditions the operator may freely rotate the piston within the cylinder so that the vehicle may leave in any desired direction.

It is to be understood that the form of my invention herewith shown and described is to be taken as a preferred example of the same and that various changes in the shape, size, and arrangement of parts may be resorted to without departing from the spirit of the invention or the scope of the subjoined claims.

I claim:

1. A hydraulic lift comprising a cylinder, a reciprocating piston arranged therein, means for supplying fluid pressure to the interior of said cylinder to lift and hold said piston, a liquid container carried by the piston and communicating at its upper end with the interior of said cylinder so as to receive the lifting and holding fluid pressure, and a discharge pipe having its lower end arranged near the bottom of said container.

2. A hydraulic lift comprising a cylinder, a hollow piston adapted to reciprocate in said cylinder, said piston and said cylinder being adapted to contain a liquid, said piston being provided with a restricted opening communicating with said cylinder below the level of the liquid therein, means for introducing fluid pressure into said piston above the level of the liquid therein, an oil container arranged in said piston and communicating at its upper end with the interior of said piston above the level of the liquid therein, and a discharge pipe having its lower end arranged near the bottom of said container.

3. A hydraulic lift comprising a cylinder, a hollow piston adapted to reciprocate in said cylinder, said piston and said cylinder being adapted to contain a liquid, said piston being open at its lower end to communicate with the interior of said cylinder, means for introducing fluid pressure into said piston above the level of the liquid therein, an oil container arranged in said piston and provided near its upper end with an opening communicating with the interior of said piston above the level of the liquid therein and a discharge pipe having its lower end arranged near the bottom of said container.

4. A device constructed in accordance with claim 3 wherein said container is arranged adjacent the upper end of said piston and provided with a tube extending therethrough.

5. A device constructed in accordance with

claim 3 wherein said piston is provided with a closure plate at its upper end provided with an opening, a plug normally closing said opening, said container being arranged adjacent said closure plate, and a tube extending entirely through said container in alignment with said plug.

6. A hydraulic lift comprising a cylinder, a hollow piston mounted to reciprocate in said cylinder and provided in its lower end with an opening, said cylinder and piston being adapted to contain a liquid, a stationary pipe extending upwardly through said opening and having its upper end arranged above the level of the liquid in said piston, the upper end of said pipe being open

and extended laterally, and means for supplying pressure fluid to the lower end of said pipe, said piston being provided with means for supplying liquid thereto through the upper end thereof. 20

7. A hydraulic lift comprising a cylinder, a hollow closed-top piston mounted for reciprocation in the cylinder, the cylinder and piston forming a pressure chamber, means 25 for communicating fluid pressure to the chamber to lift and hold the piston, and a pneumatic liquid-spraying apparatus carried by the piston and operable by the lifting and holding fluid pressure within the chamber. 30

In testimony whereof I affix my signature.
PETER J. LUNATI.
